Primary Examiner — Mary Ann Calabrese*Assistant Examiner* — Mark David Wolfley(57) **CLAIM**

The ornamental design for a dressing table, as shown and described.

DESCRIPTION

FIG. 1 is a top, front and left side perspective view of a dressing table, showing my new design;

FIG. 2 is a bottom, rear and right side perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is an enlarged view of portion 9 in FIG. 1.

The broken lines show the features of the dressing table that form no part of the claimed design. The dash-dot-dash broken lines define the boundary of an enlarged view and form no part of the claimed design.
